UNITED STATES PATENT OFFICE

ERNEST G. RIDER, OF PHILADELPHIA, PENNSYLVANIA, ASSIGNOR TO STOKES AND SMITH COMPANY, OF PHILADELPHIA, PENNSYLVANIA, A CORPORATION OF PENNSYLVANIA

BOX WRAPPING MECHANISM

Application filed September 22, 1927. Serial No. 221,201.

My invention relates to an apparatus for applying a wrapper, sheet, label or the like, either tabbed or untabbed, hereinafter generically termed a "wrapper," to a box, either stayed or unstayed, box cover, package, container structure, or the like, hereinafter generically termed a "box."

In accordance with my invention, during movement of a box and wrapper by the form block structure of a wrapping machine, a wrapper portion is folded into engagement with a box wall, particularly a side wall, and a tool actuated by the form block structure aforesaid, wipes or presses certain regions of the wrapper portion, particularly those regions adjacent the ends of said wall, into more intimate engagement therewith.

Further in accordance with my invention, during movement of a box and wrapper by the form block structure of a wrapping machine, a wrapper portion is folded into engagement with a box wall, particularly a side wall, and substantially immediately thereafter, tools actuated by the form block structure aforesaid, fold a section of the wrapper portion, particularly a corner lap, into engagement with an adjacent wall, particularly an end wall, and wipe regions of the wrapper portions adjacent the ends of the first wall into more intimate engagement therewith.

Further in accordance with my invention, a box with a wrapper adhering to its bottom is passed along a predetermined path by the form block structure of a wrapping machine or the like, and during movement of the box as effected by the form block structure aforesaid, a wrapper section, particularly a corner lap section, is folded into engagement therewith by a tool actuated by said form block structure and preferably having a component of motion in the direction of movement of the box and wrapper.

Further in accordance with my invention, a form block moving a box and wrapper along a predetermined path actuates a tool to effect a folding of a wrapper portion into engagement with a box wall, and cooperates with the tool at termination of the folding operation to maintain the tool stationary with respect to

the box and wrapper, which continue to move, to wipe the folded portion into more intimate engagement with the box wall.

Still further in accordance with my invention, during moving of a box and a wrapper along a predetermined path by the form block structure of a wrapping machine, tools actuated by the form block structure aforesaid fold a section of a wrapper portion into engagement with a box wall and, simultaneously therewith, wipe another section of the same portion into intimate engagement with an adjacent box wall. Further, if the box is unstayed, certain of the tools maintain the box wall in engagement with the form block during the operations above described.

Further in accordance with my invention, there are provided slides, units, or slide units, adjustable upon slides or guides to different positions with respect to the work-carrying structure to accommodate boxes of various sizes, each slide unit comprising a novel type of tool advanced in timed relation to the form block structure of a wrapping machine, in the path of the form block structure and actuated thereby to fold a wrapper section into engagement with a box wall during simultaneous movement of the box and tool.

My invention resides in the apparatus, structures and details of construction of the character hereinafter described and claimed.

For an illustration of some of the various forms my invention may take, reference is to be had to the accompanying drawings in which:

Fig. 1 is a side elevational view of apparatus constructed in accordance with my invention.

Fig. 2 is a vertical view, partly in section, of one of the slides or units provided with a corner lap folding tool constructed in accordance with my invention.

Fig. 3 is a side elevational view showing a corner lap folding tool while applying a corner lap section to a box wall.

Fig. 4 is a plan view of a wrapper.

Fig. 5 is a plan view, partly in section, illustrating a pair of corner lap folding members, the upper roll and brush structure being omitted for the sake of clearness.

Fig. 6 is a perspective view showing a corner lap folding tool, having a finger supporting the side wall of an unstayed box.

Fig. 7 is a perspective view showing the corner lap folding tool while applying a corner lap section to the end wall of an unstayed box.

Fig. 8 is a plan view of an assembly of the four slides or slide units for applying a wrapper to the sides and ends of a box.

Fig. 9 is a perspective view showing a corner lap folding tool while applying a corner lap section to a wall of an extension bottom box.

Figs. 10 and 11 are perspective views disclosing a corner lap folding tool, applying a corner lap section of a wrapper to a tight wrapped box, for different positions of the form block.

Figs. 12 and 13 are perspective views showing a corner lap folding tool, applying a corner lap section of a wrapper to a loose wrapped box at different positions of the plate or form block.

Fig. 14 is a plan view of a loose wrapper.

Fig. 15 is a side elevational view showing spring mechanism controlling a shaft carrying a pair of corner lap folding tools.

It is characteristic of my invention described and claimed herein that the wrapper is wiped into and maintained in intimate engagement with the wall of the box during the folding in of the corner lap sections and in the case of an unstayed box the side wall of the box is also pressed against the form block structure, the result being a well wrapped box having sharply defined and neat appearing corners.

In accordance with my invention, mechanism of any suitable type may be utilized for applying wrappers to boxes, preferably a wrapping machine broadly of the type disclosed in U. S. Letters Patent to Smith, No. 691,329, more specifically of the character disclosed in U. S. Letters Patent to Federwitz and Bailey, No. 1,541,036, U. S. Letters Patent to Nitsch and Federwitz, No. 1,540,900, and still more specifically of the type disclosed in application Serial No. 99,759, filed April 5, 1926.

The mechanism hereinafter described is related to that disclosed in my co-pending application Serial No. 99,759, filed April 5, 1926, of which this application is in part a continuation in that the corner lap sections of a wrapper are folded into adhering engagement with the box ends without necessitating pause in the movement of the box.

Referring to Figs. 1 and 8, there is shown an assembly of the slides, units, or slide units, the units 1, 1 being disposed opposite each other in cooperative relation with the sides 65 of the box B, and the units or slides 2, 2 being

disposed opposite each other and in cooperative relation with the ends of the box B.

The units 1 and 2 are mounted upon any suitable support as the base or table 3, provided with the slide or guide ways 4a upon which rest and slide the laterally projecting members 4 upon the units 1 and 2, which are adjustable toward or away from the center of the structure or machine for accommodation of boxes of different sizes and proportions as regards length of sides and ends. Any suitable means, not shown, are provided for clamping the units to the base or table 3 in their adjusted or predetermined positions. The units 1 and 2 are grouped around the platen 5, which is supported by a vertical column or plunger 6, movable vertically on the hollow support 7, and in which is disposed a spring 8 opposing downward movement of the platen 5 and restoring it to the normal position indicated in Fig. 1 upon completion of a cycle of operations. Disposed above the platen 5 is the form block or form plunger comprising the main form block 9 and the separate, supplemental or upper form block 10, the members 9 and 10 partaking of vertical movements in unison with and independently of each other, such movements having extents determined and timed by any suitable structure, as, for example, by cam structure, such as, for example, mechanism A of the aforesaid Letters Patent No. 691,329 or any equivalent structure; the members 9 and 10 corresponding, respectively, with the members 49 and 50 of said Letters Patent.

Referring to Fig. 2, unit 1 comprises the housing or casing members 11, within which is disposed the cam barrel or cylinder 12, rotatable in bearings 13, 13 and having secured thereto at one end the gear 14 driven by the gear 15, through idler gear 15a, meshing with and driven by the pinion 16 secured to or integral with a slotted hollow hub portion 16a which slidably receives the end of a splined shaft 17 having secured thereto at one end thereof, exteriorly of the casing 11, a bevel gear 17a meshing with and driven by bevel gear 17b disposed concentrically with respect to plunger 6. As indicated in Fig. 8 the gear 17b is in meshing engagement with the several bevel gears 17a and is driven in any suitable manner from a source of power to rotate the cams 12 through the mechanism described, which source of power also drives the actuating mechanism, as a cam, for the members 9 and 10.

The cam barrel 12 is provided with the circumferential continuous cam groove or slot 26 receiving the roller or cam follower 27 disposed upon the member or rod 28 comprising a sleeve portion 29 upon which rests a bracket 30 secured to said rod 28 in any suitable manner, as by a nut 31. As indicated in Fig. 5, bracket 30 comprises the oppositely extending perforated arms 30a, each receiv-

ing and being secured to a rod or member 32 mounted for free, reciprocating movement in the slide plates 11, as viewed in Fig. 2. Carried by the rods 32 at their forward ends 5 is a transversely extending supporting member 33 provided at its opposite ends with the bearing supports 34, within each of which is disposed a shaft 35 between a shoulder on which and the end of the recess or chamber 10 in the support 34 is disposed the helical spring 36 which is maintained under suitable degree of compression by adjustment of the nut 37 threaded upon shaft 35, and locked by nut 38. The spring 36 serves as a cushion resiliently opposing movement of its shaft 35 towards the left, Fig. 2. At its outward or forward ends, each shaft 35 carries a bearing member 39, in which rotates a shaft 40 on which is mounted a roller 41 of any suitable 20 material, either rigid or yielding. Supported by each member 33 is a bar 42 carrying the numerous brush units 43, said bar 42 being pivoted at 44 in the brackets 45 extending from member 33.

25 Extending downwardly as viewed in Fig. 1, from the member 33 are the arms 46, each forming a bearing support for a rod or shaft 47 mounted in a manner substantially the same as shaft 35 aforesaid. Accordingly, 30 between a shoulder on a shaft 47 and the end of the recess in arm 46 is disposed the helical spring 48 maintained under suitable degree of tension by the nuts 49 and 50 threaded on the shaft 47. At their outer ends, each shaft 47 terminates in a bearing 51, Fig. 2, in which is rotatably mounted a shaft 52 to which, substantially midway of its ends, is secured the collar 53 comprising the abutting portion 53a projecting into the path of 35 the form block structure of the wrapping machine and engaged thereby as the latter moves downwardly during a box wrapping operation. Keyed or splined to shaft 52 are the corner lap folding tools 54, comprising the 40 blade-like portions 54a, each held in a desired adjusted position longitudinally of shaft 52 in any desired manner, as by set screws 55. Also keyed or splined to the shaft 52 is a collar member 55, held in a desired adjusted 45 position longitudinally of the shaft by any suitable means, as by set screws 56, to which a plate 57 is attached, having pivoted thereto, as at 58, a wiping or holding member 59. A spring 60 connected at one end to the plate 57 and at its other end to an arm of the holding member 59 tends to effect counter-clockwise rotation of said member as viewed 50 in Fig. 6. The extent of movement of the member 59 under the influence of spring 60 is limited by suitable member 61 projecting from the blade portion 54a of the corner lap folding tool 54. In furtherance of the phase 55 of the box wrapping operation hereinafter described, it is necessary that predetermined 60 rotative movement be imparted to shaft 52,

after which it should be automatically returned to its original position. To this end, I may utilize structure of the character illustrated in Figs. 5 and 15, wherein, as shown by Fig. 5, shaft 52 extends beyond one of the bearings 51 and has secured thereto the space collars 56 and 57 between which and freely mounted on shaft 52, is the housing member 58 comprising an arm 58a normally engaging a stop member 59, carried by the member 33. The inner collar comprises an arm 56a in the outer end of which is threaded a bolt 60 held in adjusted position thereon by a nut 61. Rotatably mounted on a sleeve 58b, within housing 58, Fig. 5, is a collar 62, connected to collar 56 by a pin 63 or the like. Within the space bounded by the inner peripheral surface of housing 58 and the outer peripheral surface of collar 62 is a coiled spring 64, one end of which is secured to housing 58 at 65 and the other end to collar 62 at 66, Fig. 15.

The operation of the apparatus thus far described is as follows:

Initially, the box with a coated wrapper, 90 either tabbed or untabbed, may be manually placed upon the form block 9, 10, or automatically, as by mechanism of the general character described in the application of Federwitz and Bailey, Serial No. 40,769, filed 95 July 1, 1925, wherein boxes are individually fed beneath the wrapping machine form block structure in timed relation with the arrival of individual wrappers, either tabbed or otherwise. Regardless of what manner 100 the boxes and wrappers are fed and associated one with the other, a box B with a coated wrapper W adhering to its bottom is moved by the form block structure 9, 10 into engagement with the upper surface of the lower form block or platen 5, which yields and descends in opposition to spring 8 as the members 9 and 10 descend. As shown in Fig. 1, the upper form block is actuated, in the known manner more completely disclosed in 110 the aforesaid Federwitz et al. Patent 1,541,036, from cam 101 through levers 102, 103 and 104, the last of which is connected to the rod structure 105 whose lower end supports the form block. As cam 101, and gear 115 17b driving cams 12 and 77 rotate together, the reciprocations of the form block and operation of the wrapping tools are in timed relation. During the initial movement of 120 form blocks 9 and 10, the box and wrapper are forced downwardly past the brushes 43 and rollers 41 of the units 1, which have been advanced by their respective cam grooves 26 to positions causing the brushes to fold the side flap portions or panels α and α' of the wrapper, Figs. 4 and 14, upwardly into engagement with the sides of the box, the descending box passing the side rollers 41 immediately thereafter, whereby said side panels are forced into contact with the respective 125 130

box sides where they adhere because of the previous application of adhesive to the wrapper as a whole.

The corner lap folding operation occurs without any pause in the downward travel of the form block structure and the partially wrapped box. To this end, when cam grooves 26 function to move rollers 41 and brushes 43 to the position aforesaid, members 53a are positioned as indicated in Fig. 2. Accordingly, as the lower form block 5 moves downwardly without pausing after or during completion of the side panel folding operation, the lower surface of platen 5 beneath each side of the box engages member 53a to rotate the shaft 52 associated therewith in a clockwise direction, Figs. 2 and 3, and the similar shaft at the other side of the box in a counter-clockwise direction. On each shaft 52, 20 the corner lap folding tools 54 have been previously adjusted so that the distance therebetween corresponds substantially with the external box length. The wiping or holding tools 99 have been previously adjusted so that the distance therebetween is slightly less than the external box length, as clearly shown in Figs. 5 and 6. As shafts 52, Figs. 2 and 3, partake of clockwise rotative movement in the manner described above, tools 54 are similarly rotated and the blades thereof fold the now upstanding corner lap sections *b*, *b* into engagement with the opposite box ends. Simultaneously therewith the spring tensioned holding or wiping member 99 is brought into engagement with the side wall of the box and holds the wrapper during the corner lap folding operation, resulting in a neat appearing, smooth corner. In the case of an unstayed box the member 99 presses the side wall of 40 the box firmly against the form block while the corner lap section is being brought into adhesive engagement with the end wall of the box, resulting in an unstayed box having side and end walls at right angles to each other and to the box bottom. In a similar manner and concurrently, the shaft 52 and its associated corner lap folding tools and holding tools along the other side of the box function to fold the other pair of corner lap sections *b*1, *b*1 into engagement with the opposite box ends from the other side of the box. Ordinarily by this operation, due to the shape of tools 54, the corner lap sections aforesaid are ironed or wiped into intimate engagement with the respective box ends. Continued downward movement of the form block 5 effects continued rotative movement of the corner lap folding tools until member 53a is rotated out of the path of said form block at or after the completion of the operation. During the period in which the lower form block is in engagement with member 53a the members 99 press firmly against the side walls of the box in a region adjacent the corner of the finished box, smoothing the

wrapper and permitting the corner lap folding tools to effect a smoother application of the corner lap section to the end wall of the box. The latter result is obtained because the wrapper is held firmly against the side wall while the corner lap tool is rotating in a direction at right angles to the side wall and towards the opposite side wall; in effect, the corner lap section is stretched at the junction of the side and end walls.

It will be observed that collar 56 likewise partakes of the rotative movement of shaft 52, and during such movement the arm 56 thereof moves from its normal position, shown in Fig. 2, to and beyond the position indicated in Fig. 3. Due to the fact that arm 58a of housing 58 is in engagement with stop 59, Figs. 2 and 3, rotative movement of the housing is prevented and the end of spring 64 at 65 is held stationary. Collar 62, however, which is secured to collar 56 by pin 63, is rotated and the spring is wound to store energy therein. Accordingly, as the top of the box continuing its downward movement moves beyond member 53a, shaft 52, Figs. 2 and 3, is rotated in a counter-clockwise direction under the influence of said spring until the stop bolt 60 returns to its normal position into engagement with stop 59. The corner lap folding tools and the members 99 return to the inactive position shown in Fig. 2. Obviously, by adjustment of bolt 60 the arms 56a of collars 56, the collar 53, and its member 53a, which projects into the path of the form block, may be so adjusted that the operation of the corner lap folding members will occur at the proper time.

While the corner lap folding tools are rotating to press the wrapper section into engagement with the end of the box wall, as aforesaid, the end brushes 43 and end rolls 41 are advanced by the cam slots 26 of units 2; these end brushes and rolls being disposed vertically below the corner lap folding tools or fingers 54 as in Figs. 10 to 13. After or while the corner lap section of the wrapper is being applied to the end wall of the box, the continued downward movement of the box and wrapper past the brushes 43 of units 2 forces the end flaps *c* of the wrapper against 115 the end walls of the box and the turned-in corner laps.

When boxes of the extension bottom type are to be wrapped, the rollers 41 and the brushes 43 are replaced by a roller 42a having a longitudinal slot 42b therein in which is disposed a buffer element consisting of a longitudinal rod 42c slidable transversely in slot 42b and biased outwardly against a stop, not shown, by a spring 42d. The roller shown in Fig. 9 is of the type and operates in a similar manner to that disclosed in U. S. Letters Patent to Morrison, No. 1,348,369. After or while the corner lap section of the wrapper is being applied to the end wall of the box, the

descending extension flange of a special platen first enters the slot, as shown in Fig. 9, the roller being provided with a resilient mounting tending to maintain it in the upward position shown in that figure. A slight descent of the wall rotates the roller until the upper slot wall contacts with the edge of the flange. Further descent of the box forces the buffer rod 42e slightly inward, its inclined face, however, tending to keep the flange in constant yieldable contact with the upper wall, such descent effecting rotation of the roller 42a to bring the periphery of the roller into continuous rolling contact with the end wall of the box, forcing the wrapper against the flange and end wall in an effective manner. Before or during the corner lap turn-in operation, the members 99 are engaged by the extension edge of the platen 20 as the box descends, tensioning the spring 100. As the platen moves beyond engagement with the members, the latter, due to the spring 100, rotate counter-clockwise as viewed in Fig. 9 to stretch the wrapper tightly over the extension flange, the remainder of the operation being as heretofore described with respect to boxes of the ordinary type.

The application of a loose wrapper to a box 30 is similar to that described with respect to the application of a tight wrapper. The shaft 52 is rotated by engagement of the collar extension 53a with the downwardly moving platen to rotate the corner lap tools 35 54 which press the turn-in section of the wrapper into adhesive engagement with the end wall of the box. Continued downward movement of the form block past the end rollers 41 and brushes 43, which have been 40 advanced by the cams 12 of units 2, forces the end portion of the loose wrapper into adhesive engagement with the end wall of the box.

Completion of the box wrapping operation 45 in each of the above cases may be effected in any desired manner. As herein shown, the structure for this purpose is of the character disclosed in the aforesaid Letters Patent to Nitsch et al., No. 1,540,900, and comprises the second cam or barrel 77 rotatable in bearings 78 and having the cam slots or grooves 79 and 80. Disposed in the cam groove 79 is the roller or cam follower 81, carried upon the pin or stub shaft 82 carried by the frame or support 83 movable preferably in a rectilinear path parallel to the axis of rotation of the cam barrel 77 upon guide ways on the casing 11. Carried upon the forward end of the frame 83 is the 50 transversely extending bar or support to which is suitably secured clamping member 85, between which and the member 84 is clamped the plate or turn-in finger 86.

In the cam slot 80 is disposed the roller 55 or cam follower 87 carried by a pin or stub

shaft 88 carried by the support or frame 89, movable preferably in a rectilinear path parallel to the axis of rotation of the cam barrel 77 upon slides or guide ways of the casing 11. At its forward end, the frame 89 is provided with holes in which are supported, and longitudinally movable, the pins 90 secured to and supporting the transversely extending bar 91 upon the frame 89. The bar is recessed, as indicated in Fig. 2, and in the recess is disposed the presser bar or block 92 held in any desired position by the clamping screws 93. The presser bar 92 has upon its front face a pad 94 of felt or other suitable material.

Referring to Fig. 1, the slides or slide units 2 for applying the wrapper end panels 25 c to the ends of the box are, in general, similar to the units 1 hereinbefore described. Each comprises cam barrels or cylinders not shown, having bearings in the housing or casing 11 and driven from a shaft 17 having a bevel gear 17a secured thereto and in meshing engagement with bevel gear 17b.

The cam barrels, not shown, in the slide unit 2 are provided with cam slots or grooves with which coat, respectively, the rollers or cam followers for actuating and controlling respectively, the frames or members 33, 38 and 89. As with the units 1, the frame 33 carries the brushes 43 and roller 41; the frame 38 carries the turn-in fingers; and the frame 89 carries the presser block 92.

Upon completion of the corner lap folding operation described above, the partially wrapped box under the control of the form block structure continues its downward movement without pause, and in so doing the lower sets of brushes 43, which meanwhile have been advanced by the cam barrels of the respective units 2, fold the end panels c of the wrapper upwardly into engagement with the respective ends of the box, the descending box thereupon passing the now advanced lower side rollers 41 which force the end panels into intimate contact with the box ends.

This operation is effected without pause in the downward travel of the partially wrapped box, continued movement thereof occurring until the upper horizontal surfaces of the box sides and ends are positioned just below the turn-in fingers 86. At this time, downward movement of the partially wrapped box temporarily ceases, whereupon the cams 77 in the units 1 and the cams, not shown, in the units 2, function simultaneously to advance said turn-in fingers above the horizontal surfaces of the box sides and ends to fold all of the now vertical wrapper turn-in sections d, Fig. 5, into horizontal position, this operation being possible because the upper form block 10 has previously separated from the intermediate form block 9, and is held in a suspended position.

tion by mechanism, not shown, but well understood in the art. Upon completion of inward movement of the turn-in fingers 86 aforesaid, the upper form block 10 descends and is now supported solely upon the upper surface of said turn-in fingers. During inward movement of turn-in fingers 86 as described above, cams 77 in the units 1 and the cams, not shown, in units 2, function to 10 advance the presser blocks 92 into engagement with the exterior surfaces of the box sides and ends for applying thereto light pressure, whereby the box is steadied during the turn-in action.

- 15 As soon as the various turn-in fingers 86 have been moved inwardly to their full extent, they are immediately retracted by the various cams, with the result that the upper form block 10 drops as a dead weight into 20 the upper part of the box and on to the middle form block 9 carrying the now horizontal turn-in sections *d* of the wrapper downwardly into intimate engagement with the inside surface of the box walls and ends.
- 25 Thereafter, slight retractive movement of presser blocks 92 is effected by the cam 77 in units 1 and the cams, not shown, in units 2, whereupon the combined form block structure carries the box with the wrapper adhering thereto a slight distance downwardly, whereupon the cams aforesaid again advance the presser blocks 92 into engagement with the respective box sides and ends for exerting substantial pressure thereon, this action, 30 of course, being resisted by the intermediate and upper form blocks 9 and 10.

The wrapper application is now completed, and the wrapped box now ascends without pause, the various presser blocks, turn-fingers, rolls, brushes, corner lap finger members, etc., meanwhile having been retracted from the path of the form block structure by the various cams. During upward passage of the wrapped box as aforesaid, suitable mechanism strips the same from the intermediate and upper form block structures 9 and 10 after the latter have separated from the lower form block or platen 5.

What I claim is:

- 50 1. In a wrapping machine or the like, form block structure for passing a box and wrapper along a path, rotary structure to fold a section of a wrapper panel into engagement with a box wall, means, simultaneously operative therewith, to wipe the wrapper panel into intimate engagement with an adjacent box wall, and means actuated by said form block structure to operate said rotary structure.
- 55 2. In a wrapping machine or the like, form block structure for passing a box and wrapper along a path, rotary structure to fold a section of a wrapper panel into engagement with a box wall, means, simultaneously operative therewith, to wipe the wrapper panel

into intimate engagement with an adjacent box wall, and means projecting into the path of said form block structure and actuated thereby to operate said rotary structure.

3. In a wrapping machine or the like, form block structure for passing a box and wrapper along a path, rotary structure to fold a section of a wrapper panel into engagement with a box wall, means, simultaneously operative therewith, to wipe the portion of the wrapper panel contiguous to the fold-in section into intimate engagement with an adjacent wall, and means actuated by said form block structure to operate said rotary structure.

4. In a wrapping machine or the like, form block structure for passing a box and wrapper along a path, means for folding a wrapper panel into engagement with a box wall, means for folding a section of said panel into engagement with an adjacent wall, and simultaneously therewith, to wipe the panel into intimate engagement with said first wall, and means actuated by said form block structure to operate said second means.

5. In a wrapping machine or the like, form block structure for passing a box and wrapper along a path, a support, a shaft rotatably mounted thereon, a plurality of tools carried by said shaft for folding corner lap sections into engagement with the box ends, and for wiping the wrapper side panel into intimate engagement with the side wall of the box adjacent the ends thereof, and means, carried by said shaft, projecting in the path of said form block structure and actuated thereby.

6. In a wrapping machine or the like, means for effecting the engagement of a wrapper panel and a box side wall, a support, a shaft mounted thereon, a plurality of turn-in tools carried by said shaft to fold corner-lap sections of the panel into engagement with the box ends, a plurality of members carried by said shaft to wipe the panel into intimate engagement with the box side wall during the operation of the turn-in tool, and means actuated by the wrapping machine form block structure to rotate said shaft.

7. Mechanism for applying wrappers to boxes comprising means for passing a box and wrapper along a path, means operative while moving with respect to said path and during movement of said box to fold a section of a wrapper portion into engagement with a box wall, means operative simultaneously with said second means to wipe another section of the wrapper portion into intimate engagement with an adjacent box wall, and means actuated by said form block structure to actuate said first and second means.

8. In a wrapping machine or the like, form block structure for passing a box and wrapper along a path, rotary structure, movable parallel to a box wall, to fold a wrapper turn-in section into engagement with said wall,

5 a member simultaneously operative therewith, movable into engagement with an adjacent box wall to wipe the wrapper into intimate engagement with said last named wall, and means actuated by said form block structure to operate said rotary structure and said wiping member.

9. Mechanism for applying wrappers to unstayed boxes comprising form block structure for passing an unstayed box and wrapper along a path, means to apply a wrapper panel to a wall of the box, means to position said wall with respect to an adjacent wall, means simultaneously operative with 10 said second means to fold a section of the panel into engagement with said adjacent wall, and means actuated by said form block structure to operate said second means.

10. Mechanism for applying wrappers to 20 unstayed boxes comprising form block structure for passing an unstayed box and wrapper along a path, means to apply a wrapper panel to a wall of the box, means to position said wall with respect to an adjacent wall, 25 means simultaneously operative with said second means to fold a section of the panel into engagement with said adjacent wall, and means actuated by said form block structure to operate said first and second means.

30 11. Mechanism for applying wrappers to unstayed boxes comprising form block structure for passing an unstayed box and wrapper along a path, means to apply a wrapper panel to a wall of the box, means to wipe 35 the panel into engagement with said wall and to position said wall with respect to an adjacent wall, means simultaneously operative 40 with said second means to fold a section of the panel into engagement with said adjacent wall, and means actuated by said form block structure to operate said second means.

45 12. In a wrapping machine or the like, form block structure for passing a box and wrapper along a path, means to fold a section 50 of a wrapper panel into engagement with a box wall, means to wipe the wrapper panel into intimate engagement with an adjacent box wall, means adapted to be projected into the path of said form block structure and actuated thereby to operate said first and second means, and means operating in timed 55 relation with said form block simultaneously to advance said third means in the path of said form block structure.

55 13. Mechanism for applying wrappers to boxes comprising means for passing a box and wrapper along a path, means actuated by said first means to fold a wrapper portion 60 into engagement with a box wall comprising a member first movable in engagement with said portion transversely of and in the direction of movement of the box and wrapper, and thereafter stationary in engagement with said portion during further movement of 65 the box, means to complete application of the

wrapper to the box, and means to retract said folding means before reverse movement of the wrapped box in said path.

14. Mechanism for applying wrappers to boxes comprising form block structure passing a box and wrapper along a path, means actuated by said form block structure to fold a corner-lap portion of the wrapper into engagement with a box wall comprising a member movable in engagement with said corner-lap portion transversely of and in the direction of movement of the box and wrapper, and remaining stationary in engagement with said portion during continued movement of the box and wrapper, means to fold a 70 wrapper panel into engagement with said corner-lap and said wall during engagement between said member and said corner-lap and means to retract said folding means before reverse movement of the wrapped box in said 75 path.

15. Mechanism for applying wrappers to boxes comprising form block structure for passing a box and wrapper along a path, means actuated by said form block structure 80 to fold a corner-lap portion of the wrapper into engagement with a box wall comprising a member first movable in engagement with said corner-lap portion transversely of and in the direction of movement of the box and wrapper, and thereafter stationary in engagement with said portion during further movement of the box, means to complete application of the wrapper to the box, and means to retract said folding means before 85 reverse movement of the wrapped box in said path.

16. Mechanism for applying wrappers to boxes comprising form block structure for passing a box and wrapper along a path, 90 means actuated by said form block structure to fold a corner-lap portion of the wrapper into engagement with a box wall comprising a member first movable in engagement with said corner-lap portion transversely of and in the direction of movement of the box and wrapper, and thereafter stationary in engagement with said portion during further movement of the box, means to fold a wrapper panel into engagement with said corner-lap and wall while said member is stationary 95 and in engagement with said corner-lap, and means to retract said folding means before reverse movement of the wrapped box in said path.

17. Mechanism for applying wrappers to boxes comprising form block structure for passing a box and wrapper along a path, structure to fold a section of a wrapper panel into engagement with a box wall having components of motion in the direction of movement of said box and wrapper and transverse to said path of movement thereof, means, simultaneously operated with said folding structure to wipe the wrapper panel into 100

intimate engagement with an adjacent box wall, and means actuated by said form block structure to operate said folding structure.

18. In a wrapping machine or the like, form block structure for passing a box and wrapper along a path, structure to fold a section of a wrapper into engagement with a box wall having components of motion in the direction of movement of said box and wrapper and transverse to said path of movement thereof, means adapted to be projected into the path of said form block and actuated thereby to effect movement of said structure, and means operating in timed relation with said form block structure to advance said first means into the path thereof.
